CASSEROLE COVER

Robert R. Gibson, Horseheads, N.Y., assignor to Corning Glass Works, Corning, N.Y., a corporation of New York

Filed Sept. 12, 1969, Ser. No. 19,122

Term of patent 14 years

Int. Cl. D7—01

U.S. Cl. D44—15

Fig. 1

Fig. 2

Fig. 3

FIG. 1 is a top plan view of a casserole cover showing my new design.

FIG. 2 is a front elevational view.

FIG. 3 is a side elevational view.

The characteristic feature of the design resides in the particular ornamentation and its arrangement on the upper surface of the cover.

I claim:

The ornamental design for a casserole cover, as shown and described.
